UNITED STATES PATENT OFFICE.

JOE GOWER AND HENRY WOLFE, OF SPARTA, ILLINOIS.

COMPOSITION OF MATTER FOR USE AS A ROOF PAINT.

No Drawing.

Application filed June 17, 1922. Serial No. 569,130.

To all whom it may concern:

Be it known that we, JOE GOWER and HENRY WOLFE, citizens of the United States, residing at Sparta, in the county of Randolph, State of Illinois, have invented a new and useful Composition of Matter for Use as a Roof Paint, of which the following is a specification.

This invention relates to a composition of matter for use as a roof paint, one of the objects of the invention being to provide a paint the ingredients of which are inexpensive and which, when applied to a roof will resist the action of the elements so as to retard deterioration due either to the action of the sun's rays or to the action of moisture.

Another object is to provide a paint which is more or less elastic, thus to allow for expansion and shrinkage of the surface to which the paint is applied.

With the foregoing and other objects in view the invention consists of the following ingredients substantially in the proportions stated, to wit

Qts.

Coal tar	1 $\frac{1}{2}$
Melted rubber compound	1 $\frac{1}{2}$
Varnish	1

The ingredients above mentioned are all 30 mixed together thoroughly, the tar and rubber compound forming the body of the paint while the varnish acts as a dryer and renders the paint more lasting than would otherwise be the case. 35

What is claimed is:—

A roof paint consisting of the following ingredients substantially in the proportions stated, to wit, coal tar, 1 $\frac{1}{2}$ quarts, melted rubber compound, 1 $\frac{1}{2}$ quarts, and varnish, 1 40 quart.

In testimony that we claim the foregoing as our own, we have hereto affixed our signatures in the presence of two witnesses.

JOE GOWER.
HENRY WOLFE.

Witnesses:

W. B. McILWAIN,
FLORENCE PEEL.
